UNITED STATES PATENT OFFICE.

JOHN H. EVERSOLE, OF COLUMBUS GROVE, OHIO.

WRITING PEN.

Application filed October 21, 1925. Serial No. 63,960.

This invention relates to a pen and one object of the invention is to produce a pen point so constructed that it will not be damaged by rough usage or quickly wear out.

5 Another object of the invention is to so construct the pen point that a supply of ink may be placed in the pen holder and this ink fed through the body of the pen point to the writing end thereof.

10 The figure represents a longitudinal sectional view through the device.

The pen, which is indicated in general by the numeral 9, is provided with a shank portion 10 of an even diameter throughout its 15 length and a tapered forward end portion 11 provided with grooves 12 which correspond to the grooves 8. The shank 10 is provided with an axially disposed pocket 13 which opens through the rear end of the pen 20 and at its forward end communicates with a reduced passage 14 which extends forwardly into the tapered forward end portion of the pen and is provided with side branches 15 which open into the grooves 12 near their 25 upper ends. The staff 16 is provided with a longitudinally extending socket 17 constituting an ink reservoir and having its outer end portion 18 reduced so that the shank of the pen point 9 may fit snugly in the outer end 30 portion of this socket with its rear end abutting against the shoulder 19. A sleeve 20 may be provided upon the forward end portion of the staff 16 or may be omitted if so desired. By having the staff 16 formed with 35 a longitudinally extending socket 17 and the pen provided with a pocket 13 and passage 14 ink may be poured into the socket or reservoir 17 and when the pen is inserted the ink will flow through the shank and through 40 the passage 14 and side branches 15 into the grooves 12. It will, therefore, be seen that this construction provides a pen and holder in which a large supply of ink may be carried in the staff and fed to the pen point after the manner in which ink of a fountain 45 pen is fed to the pen. By having the passage 14 and side branches 15 of a reduced diameter, the flow of ink through the passages will be controlled by a vacuum seal which will be formed at the lower or forward 50 end of the passage 14 and, therefore, there will be no danger of too great a quantity of ink passing into the grooves 12. If desired, the rear end portion of the pen may be threaded, as shown at 21, so that it may engage with threads formed in the inner end portion of the socket and be securely held 55 in place.

Having thus described the invention, I claim:

A pen holder having a pocket opening through its forward end, and a pen point having a shank provided with a pocket opening through its upper end and aligned with the pocket of the holder to provide a relatively large ink reservoir, the pen point having a plurality of longitudinally extending grooves increasing in depth from the shank to the point terminal, said point having a central passage leading from the reservoir 60 to a point remote from the point terminal, said point having a plurality of radially disposed downwardly inclined branch passages, having their inlet ends opening into said passage and their outlets opening into 65 the bases of the grooves at points of their greatest depth.
